Primary Examiner — Mitchell I. Siegel

CLAIM

The ornamental design for a golf club head, as shown and
described.

DESCRIPTION

FIG. 1 is a top perspective view of a golf club head;
FIG. 2 is a bottom perspective view of the golf club head of
FIG. 1;

FIG. 3 is a front elevational view of the golf club head of
FIG. 1;

FIG. 4 is a rear elevational view of the golf club head of FIG.
1;

FIG. 5 is a top view of the golf club head of FIG. 1;

FIG. 6 is a bottom view of the golf club head of FIG. 1;

FIG. 7 is a left side view of the golf club head of FIG. 1;

FIG. 8 is a right side view of the golf club head of FIG. 1;

FIG. 9 is a top perspective view of a second embodiment of

a golf club head;

FIG. 10 is a bottom perspective view of the golf club head

of FIG. 9;

FIG. 11 is a front elevational view of the golf club head of
FIG. 9;

FIG. 12 is a rear elevational view of the golf club head of
FIG. 9;

FIG. 13 is a top view of the golf club head of FIG. 9;

FIG. 14 is a bottom view of the golf club head of FIG. 9;

FIG. 15 is a left side view of the golf club head of FIG. 9;

and,

FIG. 16 is a right side view of the golf club head of FIG. 9.

The broken line showing is included for the purpose of
illustrating unclaimed subject matter and forms no part of

the claimed design.

1 Claim, 16 Drawing Sheets
